UNITED STATES PATENT OFFICE.

AMELIA MORSE, OF NEW YORK, N. Y.

DESIGN FOR A FIGURE TOY.

50 318.

Specification for Design.

Patented Feb. 13, 1917.

Application filed December 5, 1916. Serial No. 135,277. Term of patent 7 years.

To all whom it may concern:

Be it known that I, AMELIA MORSE, a citizen of the United States, and a resident of the city of New York, borough of Manhattan, in the county and State of New York, have invented a new, original, and ornamental Design for a Figure Toy, of which the following is a specification, reference being had to the accompanying drawing, forming part thereof.

The figure is a perspective view, showing my new design.

I claim:

The ornamental design for a figure toy, as shown.

AMELIA MORSE.
